UNITED STATES PATENT OFFICE.

JOHN J. KNAPP, OF THE UNITED STATES NAVY, AND GEORGE W. DUNN,
OF WASHINGTON, DISTRICT OF COLUMBIA, ASSIGNORS TO JOHN J.
KNAPP, TRUSTEE, OF WASHINGTON, DISTRICT OF COLUMBIA.

BREECH-LOADING ORDNANCE.

SPECIFICATION forming part of Letters Patent No: 783,050, dated February 21, 1905.

Application filed June 10, 1904. Serial No. 212,009.

To all whom it may concern:

Be it known that we, JOHN J. KNAPP, lieutenant-commander United States Navy, stationed at the Navy-Yard, Washington, District of Columbia, and GEORGE W. DUNN, of Washington, District of Columbia, citizens of the United States, have invented certain new and useful Improvements in Breech-Loading Ordnance; and we do hereby declare the following to be a full, clear, and exact description of the same, reference being had to the accompanying drawings, forming a part of this specification, and to the letters of reference marked thereon.

This invention has for its object primarily to provide an effective means for preventing the "flare-back" or the escape from the breech of a gun of the gaseous products or of any residue or material remaining in the gun after a discharge, although by the use of the present invention it is designed not only to accomplish these objects, but also to effectually clean the bore of the gun prior to the entire removal of the breech-block of all products or matter remaining in the bore and breech-chamber of the gun, as well as to provide a means whereby the temperature of the gun may be kept down to overcome the liability of the premature discharge of the next succeeding charge, or the deterioration of said charge should it remain in the gun for any length of time without being fired.

A further object of the invention is to provide a device of such character that it may be readily applied to guns at present in use without the necessity of alteration such as would require the dismounting and returning of the guns to the shops and which when applied will not to any appreciable extent change the balancing-point of the gun or in any way affect its normal accuracy and operation.

A further object of the invention is to provide a means whereby the gun may be cleared of objectionable products remaining after a discharge without imposing upon the gun crew any labor or care other than is ordinarily required in the opening of the breech, the recharging of the gun, and the closing of the

breech. In other words, in accordance with this feature of the invention the apparatus is made automatic in its action and is controlled in its operation by the parts which are ordinarily and necessarily moved in opening and closing the breech-chamber of the gun.

A still further object of the invention is to provide a mechanism which will not be liable to destruction by reason of the recoil movements of the gun.

Referring to the accompanying drawings, Figure 1 is a perspective view looking at the breech of an eight-inch gun, the gun itself, with its attachments and working parts, being shown in dotted lines and the portion of the apparatus pertaining to the present invention being shown in full lines. Figs. 2 and 3 are detail diagrammatic views illustrating more particularly the details of construction of the apparatus and showing its application to the gun. Figs. 4, 5, and 6 are details of the valve, handle telescoping sections, and relief-valve, respectively.

Like letters of reference in the several figures indicate the same parts.

The gun illustrated in the accompanying drawings is of a well-known type and will not be particularly described further than to say that the stationary portion of the mount or carriage is indicated by the letter A, the slide pivoted in the carriage by the letter B, and the body of the gun by the letter C. Provision is made for recoil action in the usual manner and suitable recoil-checks, such as indicated at D, are provided for arresting the recoil and returning the gun to its normal position.

The removable breech-block is shown in Fig. 1 in its open position, and from this figure it will be seen that the gun is, as heretofore, provided with an enlarged chamber for the reception of the breech-block and a reduced bore, the rifling of the latter being shown in Fig. 2.

In accordance with the present invention provision is made for injecting a medium of a gaseous or fluid nature into the breech of the gun during the initial stages of the opening

movement of the breech-block, the injection of this medium continuing for a period sufficiently long to insure the sweeping or cleaning out of the gun throughout its whole length 5 and the effectual extinguishment of any burning material or material liable to ignite upon exposure to air. The medium which is injected in the breech of the gun may for convenience be termed a "cleaning" medium, 10 and it may consist of air or water or a mixture of air and water, with either or both of which chemicals may be combined to increase the cleaning or extinguishing effects, said medium being forced into the breech of the gun 15 under high pressure and preferably through a nozzle or nozzles opening into the breech-chamber around the breech-block when in place in the gun.

Referring to Fig. 1, it will be seen that, as 20 illustrated, two nozzles are provided in the gun, said nozzles being lettered E. Said nozzles have their apertures, as before stated, in the enlarged breech-chamber, and they are so positioned and pointed as to direct the medium 25 issuing therefrom in spiral lines toward the nozzle of the gun. The angle of the nozzles is preferably such that their discharge will just escape the shoulder at the inner end of the breech-chamber and will enter the bore of 30 the gun with a swirling motion conforming in a greater or less degree to the spiral lines of the rifling in the bore. The nozzles may be formed by simple ducts in the wall of the gun itself or ducts may be formed in the gun and 35 suitably lined to constitute the nozzles, as may be found most desirable. For supplying the cleaning medium to the nozzles branch ducts F extend from their outer ends to a suitable valve to be presently described, in which they 40 unite and to which the medium is supplied under pressure by a duct in communication with any suitable source, such, for instance, as an air-pressure system and the water-pressure system, the two systems being indicated 45 diagrammatically in Fig. 2 at g and g', respectively.

The valve before referred to is preferably a valve which will control the supply of cleaning medium to both nozzles, or a greater or 50 less number of nozzles are employed will control the supply of cleaning medium to all of the nozzles employed, and it is preferably an automatic valve—that is to say, a valve which will be automatically opened by the opening 55 of the breech-block and again closed after it has remained opened for a sufficient length of time. As illustrated, the valve is of an ordinary type of plug-valve adapted to be opened or closed by means of a handle or projection 60 H, connected with the upper portion of the valve-stem h. The projection H extends into the path of the breech-block or into the path of a projection thereon and is adapted to be moved so as to open the valve by the movement of the breech-block itself as it moves to

its open position. As illustrated, the handle or projection on the valve extends into the path of the spiral projections on the breech-plug, which constitute one of the portions of the mutilated thread for holding the breech-block 70 in its closed position. Thus the turning of the breech-block does not of itself release or open the valve; but the initial outward movement of the breech-block instantly opens the valve, and the injection of the cleaning, cooling, and 75 extinguishing medium commences simultaneously with the opening of a vent around the breech-block, thus enveloping the breech-block in said medium, and the instant the bore of the gun is opened any and all products or 80 material remaining in said bore and around the inner portion of the breech-block will be affected by the said medium and ordinarily will be swept forwardly and out of the muzzle of the gun before the breech-block reaches its 85 full open position or a sufficient aperture is formed to permit of a flare-back. It is obvious that the valve, having been opened by the opening movement of the breech-block, could be permitted to remain opened until 90 closed by hand or until an inspection through the breech-opening discloses the fact that the gun had been effectually cleaned, or if cooling be the object sought to be attained it could remain open until sufficiently cooled by the medium injected through the nozzle. In the preferred arrangement, however, the valve is adapted to be automatically closed by a spring, (indicated at I in Fig. 2,) such spring operating to return the valve to its normal position the instant the breech-block moves out of engagement with the handle or projection. It will be understood, however, that the valve may be opened by hand at any time and held 100 opened should it seem necessary or desirable 105 to continue the injection of the cleaning and cooling medium for a longer period. To permit the breech-block to be again entered into its chamber without affecting the valve itself, the end of the handle or projection is preferably arranged to yield upon the return movement of the breech-block, and for this purpose the arrangement may be as illustrated, wherein the end of the projection or handle adapted to engage the breech-block is shown 115 in the form of a spring-pressed pawl K, having one of its faces k inclined at such an angle that on the return movement of the breech-block the pawl will be retracted without affecting the valve; but on the opening movement of the breech-block the pawl will engage therewith and cause the valve to be 120 opened, as before described.

Inasmuch as the gun has a recoil movement, it is necessary to provide some means where- 125 by the medium for cleaning, cooling, &c., may be conveyed to the valve and nozzles without danger of having the connections broken by the said recoil movement. Obviously extensible or flexible connections may 130

be employed, and in the preferred arrangement an extensible or flexible connection in the form of a duct having telescopic sections extending parallel with the recoil movements 5 is employed. One of said sections is connected with the gun-mount and another with the gun itself, whereby the sections may move with relation to each other without disrupting the continuity of the duct. As illustrated in the accompanying drawings, a cylinder M, constituting one of the telescopic sections of the duct, is secured to the gun-mount, preferably by brackets m, which may for convenience be connected with the supports 10 for one of the recoil-check cylinders, and sliding into this cylinder through a stuffing-box n is a telescopic section N, secured at its outer end by a bracket O to a portion of the gun itself. The telescopic section N forms a continuation of a pipe O', leading to the valve, and it will be understood that the two telescopic sections N and M extend in a line parallel with the line of gun movement during recoil. A flexible hose or metallic swivel-joint, preferably a metallic hose, (indicated at P,) connects with the forward end of the cylinder M, and from the hose P suitable connections at p and p' extend to air and water systems or supplies for feeding air or water 20 under pressure, in practice such pressure being preferably in the neighborhood of two hundred pounds to the square inch, although wide variation may be made without departing from the invention.

35 To prevent any possibility of a bursting pressure in the system, a relief-valve Q is provided; such valve being loaded to maintain the required pressure in the system and to permit of an escape should the pressure exceed the limit.

40 It will be noted particularly that the flexible hose or jointed connection P permits of the gun movements for elevation and depression, while the telescopic sections permit of the gun movements for recoil action, and such parts are preferably made relatively light, so as to avoid any appreciable increase in the weight on one side of the pivot of the gun. As a consequence the entire attachment does 45 not appreciably alter the balance of the gun nor does it in any way affect the accuracy or the convenience and speed with which the ordinary manipulations of the gun may be performed.

55 The cooling effect of the medium due to its expansion as it leaves the nozzles within the breech of the gun is a material factor in keeping down the temperature of the gun, and in operation it is found that the expansion of 60 the medium, together with the air drawn in with the same around the breech-block during the opening of the latter, is sufficient in volume to entirely fill the bore of the gun almost instantly and to form a violent sweeping draft through the gun from the breech to

the muzzle, thereby effectually preventing any possibility of a flare-back or the escape into a turret of any of the gases, sparks, burning or partially-burned powder-bags, or any material liable to remain in the gun after a shot 70 has been fired.

In addition to the advantages enumerated the arrangement is effective in preventing a "hang-fire." For instance, when the primer is fired and the cartridge-bag ignited without 75 igniting the charge the bag smolders and on the opening of the breech is formed into a flame; but with the present arrangement a strong force of water may be turned on and the breech-plug just started, so that the water will extinguish the smoldering bag before the access of air thereto.

Having thus described our invention, what we claim as new, and desire to secure by Letters Patent, is—

85

1. In a cleaner for the purpose specified, the combination with the gun and removable breech-block therefor, of the supply for cleaning medium, nozzle for directing the cleaning medium into the breech of the gun and a valve 90 controlling said supply having an operating-handle extending into the path of the breech-block to be moved thereby to open the valve and contacting with a side portion of the breech-block to hold the valve open during the 95 opening movement of the breech-block; substantially as described.

2. In a cleaner for the purpose specified, the combination with the gun and removable breech-block therefor, of the supply for cleaning medium, nozzle for directing the cleaning medium into the breech of the gun and a valve controlling said supply having an operating-handle extending into the path of the breech-block to be moved thereby to open the valve, 100 and having a yielding end portion to permit the breech-block to return to its seat when the valve is closed.

3. In a cleaner for the purpose specified the combination with the gun and removable 110 breech-block therefor, of the supply for cleaning medium, nozzle for directing the cleaning medium into the breech of the gun and a valve controlling said supply having an operating-handle with a yielding end portion extending 115 into the path of the breech-block to be moved thereby to open the valve, and contacting with a side portion of the breech-block to hold the valve open during the opening movement of the breech-block, said yielding end portion 120 permitting of the return of the breech-block to its seat when the valve is closed.

4. In a cleaner for breech-loading ordnance, the combination with the gun and removable breech-block, of a nozzle and supply-duct for the cleaning medium, a cock for opening and closing the same, a spring for automatically closing the cock and a projection for opening the cock adapted to be moved by the opening of the breech-block; substantially as described. 130

5. In breech-loading ordnance, a supply for cleaning medium and a self-closing valve and means whereby said valve is automatically opened by the opening of the breech; substantially as described.

6. In breech-loading ordnance, the combination with the gun-mount, the gun movably mounted thereon and a nozzle for the admission of cleaning medium to the breech of the gun; of an extensible duct for the supply of cleaning medium and a relief-valve in said duct; substantially as described.

7. In breech-loading ordnance, the combination with the gun-mount the gun movably mounted thereon and a nozzle for the admission of cleaning medium to the breech of the gun, of a duct embodying telescoping sections one connected with the mount and another with the gun and a relief-valve in said duct; substantially as described.

8. In breech-loading ordnance the combination with the gun and nozzle directed into the breech of the gun, of an air-supply duct

and a water-supply duct both communicating with said nozzle and a single valve controlling the admission of both air and water; substantially as described.

9. In breech-loading ordnance, a supply for cleaning medium, a self-closing valve, means whereby the valve is automatically opened by the initial opening movement of the breech-block and means whereby it is automatically held open during the continued opening movement of the breech-block.

10. In breech-loading ordnance, a supply for cleaning medium, a self-closing valve, means whereby the valve is automatically opened by the opening movement of the breech-block and means whereby the breech-block may be returned to its seat while the valve is closed; substantially as described.
